D. HURLEY.
LADY'S RAIN SUIT.

APPLICATION FILED JUNE 1, 1907.

927,542.

Patented July 13, 1909.

UNITED STATES PATENT OFFICE.

DELILA HURLEY, OF RICHMOND, INDIANA.

LADY'S RAIN-SUIT.

No. 927,543.

Specification of Letters Patent.

Patented July 18, 1909.

Application filed June 1, 1907. Serial No. 376,798.

To all whom it may concern:

Be it known that I, DELILA HURLEY, a citizen of the United States, residing in the city of Richmond, in the county of Wayne 5 and State of Indiana, have invented a Lady's Rain-Suit, of which the following is a full and accurate specification.

My present invention relates to a two-piece garment for ladies; and the object of 10 the invention is to provide a two-piece rain-suit for ladies' wear, to be made, preferably, of oil-cloth or rubber goods.

A further object is to provide a lady's rain-suit which will be neat and attractive in appearance, strong and durable in construction, 15 and which can be manufactured and sold at a comparatively low price. And, finally, my object is to provide a lady's two-piece rain-suit which may be easily donned, or quickly 20 dispensed with, and which when in use will effectually cover and protect the costume of the wearer.

Other objects and particular advantages 25 of my invention will be referred to in the following specification, and the construction and advantages of the invention are apparent from the accompanying drawings.

One manner of carrying out the objects of my invention, and that which in practice has 30 been found to be the most practical, is shown in the accompanying drawings, in which—

Figure 1 shows my invention complete and in operative position, as it would appear when being worn. Fig. 2 is an inside plan 35 view of the skirt member of the suit. Fig. 3 is an inside view of the jacket member of the suit. Fig. 4 is a face view of a portion of one of the sections of the skirt showing the arrangement of the eyelets. Fig. 5 is a face 40 view of a portion of one of the sections of the jacket, showing the arrangement of the eyelets.

Similar reference characters denote like parts throughout the several views.

Referring now to the drawings in detail: The jacket section comprises a triangular back-member 1 having permanently secured thereto the two oppositely disposed complementary members 2 and 3, the said three 50 members, when joined, form a semicircular body, the edges being hemmed and reinforced by tape, the latter being designated by the letter *a* in Fig. 3. Said tape is attached by first sewing one of its edges to the 55 raw edges of the garment, after which the

edge of the garment is turned in forming a hem, and then the other edge of the tape is stitched to the inner face of the garment, by which it is apparent that only one seam appears on face of the garment. The seam 60 formed by joining the members 1 and 2 is covered and reinforced by the tape *b*, stitched on each side thereof; while the seam formed by joining the members 1 and 3 is covered and reinforced by the tape *c*, stitched 65 on each side thereof.

The letter *x* denotes the neck aperture formed by the curvature of the upper end of the members 1, 2 and 3.

The numerals 4 and 5 designate sleeves 70 which are joined to the jacket at points on a line with the seams connecting the members 1—2 and 1—3, respectively, the seams joining the sleeves to the jacket are covered and reinforced by tape, designated by letters 75 *d* and *e* respectively.

A pocket 6 is attached to the outer face of the member 3 as shown in Fig. 1.

Secured near the inner face of the edge of the member 3, to the tape *a*, are a plurality of 80 eyelets 7, as shown in Fig. 3, and corresponding therewith are a like number of studs 8 secured to the outer face and near the edge of the member 2, which studs are adapted to be pressed into said eyelets and detachably held 85 in place by a slight contraction of the eyelets.

The skirt section is composed of six gored members designated by the numerals 9, 10, 11, 12, 13 and 14, and they are secured together and adapted to fit around the waist of 90 the wearer, the smaller ends being curved to suit the waist thereby forming the waist aperture *Z*, and the larger or lower ends are formed rounding to form the bottom of the skirt.

The upper edge of the skirt, around the waist aperture, is bound with the tape *f*. The bottom of the skirt is reinforced by the tape *g*. One edge of said tape is first sewed to the face side of the lower edge and it is then 100 turned over upon itself, a hem is then turned on the lower edge of the skirt, and then the other edge of the tape *g* is stitched to the skirt above said hem. Like unto the above the free edge of the member 14 is hemmed, 105 the tape *h* being employed in this instance. And also like unto the above the free edge of the member 9 is hemmed, the tape *j* being employed in this instance, the only difference in this from the other edge being that the hem 110

is made wider, that is it is turned in farther, as shown in Fig. 2.

Secured to the inner face of the edge of the member 9 are a plurality of equally disposed 5 eyelets 15; and secured to the outer face of the edge of the member 14 are a like number of correspondingly disposed studs 16, shown in Fig. 4, which are adapted to be pressed into said eyelets in order to hold the skirt in 10 the position shown in Fig. 1.

The seams joining the members 9—10, 10—11, 11—12, 12—13, and 13—14 are reinforced by the separate lengths of tape *k*, *m*, 15 *n*, *p*, and *r*, respectively, which are stitched on each side of the seams and on the inside of the skirt, all substantially as indicated in Fig. 3.

At a convenient point there is formed a slot through the skirt, as for instance the slot 20 17 which is formed by leaving out a part of the tape *m* and not connecting the members 10 and 11 at that point. Said slot is to provide means for the wearer to reach through the skirt for the purpose of holding up the 25 skirt of the dress garment.

Having now fully shown and described my

invention, what I claim and desire to secure by Letters Patent of the United States, is—

In a rain suit, the combination of a skirt and waist, the skirt formed of a plurality of 30 parts sewed together, a tape secured to the raw edge of each seam and then turned and the free end sewed to the garment so as to cover the seam an aperture formed in a seam for giving access to the dress underneath when in use, the parts of the skirt shaped in such a manner that when the completed garment is laid flat it will form the arc of a circle, the smaller edge "f" forming the 35 waist band and a means for securing the garment after putting it on, consisting of a series of studs secured on the under side of the overlapping edge and fitting into eyelets secured to the upper side of the other edge.

In testimony whereof I have hereunto subscribed my name in the presence of two subscribing witnesses.

DELILA HURLEY.

Witnesses:

JULIA McLANE,
R. W. RANDLE.
